UNITED STATES PATENT OFFICE.

FRANK X. ENDERLE, OF LOS ANGELES, CALIFORNIA.

CONCRETE BURIAL-VAULT CONSTRUCTION.

1,404,944.

Specification of Letters Patent. Patented Jan. 31, 1922.

Application filed February 28, 1921. Serial No. 448,292.

To all whom it may concern:

Be it known that I, FRANK X. ENDERLE, a citizen of the United States, residing at Los Angeles, in the county of Los Angeles, State 5 of California, have invented new and useful Improvements in Concrete Burial-Vault Construction, of which the following is a specification.

This invention relates to burial vaults, and 10 more particularly to that class of vault which is preferably formed of cement and adapted to be lowered into a grave for the reception of the usual casket containing the remains, and which has a self-sealing cover adapted 15 to be sealed thereon after the casket has been deposited therein.

The main object of this invention is to provide a receptacle for the purpose above set forth, having a groove formed in the upper 20 edges of its walls, for the reception of a cement mixture in liquid form or other adhesive material, and a cover having a corresponding tongue member adapted to project into said groove, the tongue member and the 25 groove being of such shape in cross section that the cement mixture in said groove will be caused to spread in an even layer to fill the interstices between the surfaces of the tongue member and the opposed walls of the 30 groove, as well as between the lower surface of the lid and the upper surface of the receptacle body, thereby forming a hermetical seal between the lid and body of the receptacle after the cement mixture therebetween has 35 become set.

A further object of this invention is to so shape the tongue member and the corresponding groove as to cause the major part of the surplus liquid cement mixture in the groove 40 to flow toward the outside edges of the receptacle, when the cover is being placed in position, thereby preventing said cement liquid mixture from falling into the receptacle and defacing the casket.

45 Other objects will appear in the following description, will be pointed out in the claim, and will be embodied in the accompanying drawings, in which:—

Fig. 1 is a longitudinal vertical section 50 through a vault of the type above described, embodying the invention.

Fig. 2 is a transverse section through the same, taken on the line 2—2 of Fig. 1.

In constructing the vault in accordance

with my improvements, I provide a receptacle 5 and a cover 6. The receptacle 5 comprises the bottom 7, the side walls 8 and the end walls 9, all of which are preferably formed of reinforced concrete and suitably water and air proofed. The upper ends of 60 walls 8 and 9 are provided with a flange 10 which serves to broaden the upper surfaces thereof, said surfaces being provided with a continuous groove or depression 11 adapted to receive the tongue member 12 formed on 65 the cover 6.

The cover 6 is preferably arched in cross section as at 13 and is provided with bevelled ends as at 14 and is also preferably reinforced and made both moisture and air tight. 70 The cover 6 is provided on its inner arched surface with strengthening ribs 15 which are broader and deeper at their central portion than at the extremities which join with the edges thereof.

75 The tongue member 12, in cross section, is formed in the shape of a quadrant, having the vertically disposed inner surface 16 and the curved lower and outer surface 17, and the groove or depression 11 is correspondingly shaped to receive said tongue, which is adapted to fit therein.

The receptacle 5 is adapted to be lowered into the grave in any convenient manner, the groove and depression 11 having been previously filled with a suitable moist grout or plastic material 18, the casket is then lowered into the receptacle, and the cover is then lowered down on to the receptacle by means of grappling apparatus adapted to engage in notches 19 formed in the edges thereof.

85 As the edge 20 formed at the junction of the surfaces 16 and 17 of tongue 12 comes in contact with the grout in groove 11 a dividing action is imparted thereto thus serving to effectively spread said grout in an even layer between the adjacent surfaces, the surplus portion of the grout being forced to the outside, due to the fact that less resistance is given the material through the curved passage than through the vertical passage. 95 After the grout becomes set it will be seen that a perfect air tight juncture between the receptacle and cover will be formed, and that the seal is formed without the necessity of the mason being lowered into the grave for 100 this purpose.

What I claim is:

A vault, comprising a body member having in the upper surface of its walls a continuous groove adapted to receive a plastic sealing material, and a cover provided with a tongue adapted to project into said groove, said tongue and groove being quadrantal in

shape and each having its inner wall arranged in a vertical plane.

In witness that I claim the foregoing I 10 have hereunto subscribed my name this 3rd day of February, 1921.

FRANK X. ENDERLE.
